DESIGN FOR A HAT

Arthur J. Stack, Westport, Conn., and Aly C. Moran, New York, N. Y., assignors to Hat Corporation of America, Norwalk, Conn., a corporation of Delaware

Application June 27, 1941, Serial No. 101,733

Term of patent 3½ years

To all whom it may concern:

Be it known that we, Arthur J. Stack and Aly C. Moran, citizens of the United States, residing respectively at Westport, in the county of Fairfield and State of Connecticut, and at New York, in the county of New York and State of New York, have invented a new, original, and ornamental Design for a Hat, of which the following is a specification, reference being had to the accompanying drawing, forming a part thereof, and in which:

Fig. 2 is a top perspective view of the hat shown in Fig. 1.

We claim:

The ornamental design for a hat, as shown.

ARTHUR J. STACK.
ALYS C. MORAN.
